REMOVABLE TYPE FOURDRINIER PAPER MAKING MACHINE

Original Filed Sept. 19, 1925 2 Sheets-Sheet 2

UNITED STATES PATENT OFFICE.

ALONZO ALDRICH AND EARL E. BERRY, OF BELOIT, WISCONSIN, ASSIGNEES TO
Beloit Iron Works, A CORPORATION OF WISCONSIN.

REMOVABLE TYPE FOURDRINIER PAPER-MAKING MACHINE.

Original application filed September 19, 1925, Serial No. 57,272. Divided and this application filed December 8, 1926. Serial No. 153,233.

This invention relates to improvements in a removable table type of Fourdrinier paper making machine.

The embodiment of our present invention disclosed in this application was originally disclosed in our copending application Serial No. 57,272, filed September 19, 1925, of which the present application is a division, and in part in our copending application Serial No. 153,234, filed December 8, 1926.

It is an object of this invention to provide an improved Fourdrinier construction where-in the table is laterally removable as a unit upon tracks adapted to be permanently associated with the Fourdrinier structure, said tracks being slidably mounted for transverse movement and forming the support for said table unit, both in operative and removed position.

Other and further important objects of this invention will be apparent from the disclosures in the specification and accompanying drawings.

This invention (in a preferred form) is illustrated in the drawings and hereinafter more fully described.

On the drawings:

Figure 1 is a fragmentary diagrammatic side elevational view of a Fourdrinier paper making machine, showing a table and supporting structure embodying the principles of this invention.

Figure 2 is an enlarged broken transverse elevational view.

Figure 3 is a broken top plan view with the table removed.

Figure 4 is an enlarged fragmentary view taken substantially on line IV-IV of Figure 3.

Figure 5 is an enlarged sectional view taken on line V-V of Figure 2 with parts removed.

As shown on the drawings:

There is shown in Figure 1 a portion of a Fourdrinier paper making machine of the removable table type embodying the principles of our invention. The reference numeral 1 indicates a supporting structure as a whole, comprising a pair of longitudinal I-beams 2 spaced apart by means of transverse beams 3 (Figure 2) bolted thereto. Mounted on said supporting structure 1 are a plurality of transverse I-rails 4, which together with the I-beams 2 and transverse beams 3 form a

sub-structure on which a table structure 5 is adapted to be supported when in operative position. The rails 4 also serve, as will later be explained, as tracks on which the table is adapted to be moved when a wire is being changed. Said table structure 5 comprises a pair of table rails 6 supporting the usual table rolls 7 and suction boxes 8. A wire guide roll 9, a wire stretch roll 10 and an inside wire roll 11 are indicated on the drawings. A breast roll 12 and a lower couch roll 13 are supported independently of the table structure. A wire 14 is shown in normal position passing around said breast and couch rolls and over said table rolls. It should be noted that the rolls 10 and 11 are so positioned as to carry the lower run of the wire 70 below the level of the bottom flanges of the tracks 4. The importance of this feature will be explained later. Return wire rolls 15, supporting the lower run of the wire 14, are journaled in bearings carried by the supporting beams 2. Any suitable shaking mechanism may be associated with the breast roll or table structure or both.

The table rails 6 are supported in operative position by flanged rollers 16 running on said tracks 4, said rollers being operated by means of a driven shaft 17 to cause the table structure 5 to roll as a unit over the tracks 4. The table rails 6 are tied together by means of transverse bars 18 to form a unitary table structure 5. Said table rails 6, which are preferably formed of channel iron, support from their lower flanges a plurality of hollow brackets 19 (Figure 2) which form the bearings for the driving shaft 17. The flanged rollers 16 are adapted to be housed in pairs within said hollow brackets 19. The hollow bracket 19 on the back end of each of the beams 18 is drilled and threaded to receive a locking screw 21 secured to the track 4 for locking the table structure in place. The tracks 4, which will hereafter be designated as the inner tracks, are each slidably mounted at one end upon rollers 22 supported from a roller carrying frame 23. Said frame 23 in turn is supported from the rear I-beam 2 and a bracket 24 bolted to the web and upper flange thereof. Said frame 23 carries in addition to the spaced lower rollers 22, cooperating bevelled rollers 25 mounted directly above said rollers 22 and adapted to

bear against the upper surface of the lower flange of the I-rail 4 (Figure 4). Said bevelled rollers 25 are rotatably mounted upon pins 26 carried by upstanding portions 27 and 28 of the frame 23. A pair of oppositely positioned adjusting bolts 29 are also carried by said upstanding portions 27 and 28 and are adapted to abut opposite surfaces of the web of the track 4 for the purpose of maintaining said track in vertical position. The bevelled rollers 25 serve to hold the track 4 in bearing relation with the rollers 22 and since the rollers 22 are spaced apart, said track 4 is supported during movement in horizontal position.

The other end of each of the tracks 4 is adapted to be supported in normal position on a shoe 30 formed on a roller carrying frame 31 mounted upon the front beam 2. Said roller carrying frame 31 is in general similar in construction to the roller carrying frame 23 and is secured as by means of bolts and a bracket 32 to said beam 2. The shoe 30 is provided with a curved surface 33 onto which the rail 4 is adapted to slide. A housing 34 is also mounted on said roller carrying frame 31 over the shoe 30 and is adapted to serve as a stop for limiting the forward movement of the track 4. Adjustable bolts 35 are supported from said housing 34 in a similar manner to the bolts 29 and serve to maintain the track 4 in vertical position.

In the same way as tracks 4 are adapted to support the table structure 5 in normal position, similar tracks 36 are provided to support the table in removed position. Said tracks 36 are each adapted to lie parallel and adjacent to a track 4 and are each slidably mounted upon rollers 37 on the roller carrying frame 31. Cooperating sets of bevelled rollers 38 mounted directly above the rollers 37 serve to hold said tracks 36 in horizontal position during movement thereof. A shoe 39 mounted upon the roller carrying frame 23 is adapted to support the other end of each of the tracks 36. Said tracks 36 are adapted to be rolled out of the front side of the machine and are each provided with a roller 40 at their forward ends for sliding movement over a floor 41. Said roller 40 is journaled in a dependent bracket 42, which limits the movement of the rail 36 in the opposite direction by abutment against the roller frame 31.

When the paper machine is operating, both sets of tracks 4 and 36 are in telescoped position lying between the supporting front and rear beams 2. In order to change the wire, the tracks 36 are pulled out on the front side of the machine and the table structure 5 rolled out over them. The housing 34 is provided with a flange 43 on its upper surface to form a continuation of the track 4 for the rollers 16 to run on. While the table is raised upon the tracks 36, the tracks 4 are pulled at the rear to allow a new wire to be strung in

position. The tracks 4 are then run back into place and the table rolled back over them and locked by means of the locking bolt 21. The tracks 36 are again rolled into telescoped position and the operation completed. The paper machine may be operated with the tracks 4 and 36 in telescoped position for the reason that the lower run of the wire extends below said tracks and therefore does not interfere therewith.

It will thus be apparent that we have provided a simplified structure whereby a considerable amount of time and labor is saved in the changing of wires on paper machines. It should be particularly noted that the inside tracks 4 form a permanent part of the table structure on which the table unit is adapted to normally rest. Since the tracks 4 and 36 are mounted on roller bearing surfaces and are supported in unbalanced position by means of the spaced bevelled rolls 25 and 38 and the flanged rollers 22 and 37, the effort required in moving the tracks 4 and 36 into and out of position is very slight.

We are aware that many changes may be made, and numerous details of construction may be varied through a wide range without departing from the principles of this invention, and we therefore do not purpose limiting the patent granted hereon, otherwise than necessitated by the prior art.

We claim as our invention:

1. In a paper making machine, a table structure and a plurality of pairs of track members on which said table structure may be removed, each pair of said track members comprising parallel, slidable tracks adapted to be extended from the machine in opposite directions.

2. In a paper making machine, a table structure, a wire associated therewith, and a plurality of pairs of track members on which said table structure may be removed, each pair of said track members comprising parallel, slidable tracks adapted to be extended from the machine in opposite directions and normally positioned above the lower run of the wire.

3. In a paper making machine of the removable Fourdrinier type, a laterally removable table structure, a supporting structure therefor, I-rails on which said table structure is normally supported and on which said table may be removed and spaced flanged rollers mounted from said supporting structure on which said I-rails are adapted to be rolled transversely of said machine, certain of said rails in extended position forming supports for said table structure when said table is removed from its normal position in said machine.

4. In a paper making machine of the removable Fourdrinier type, a laterally removable table structure, a supporting structure therefor, I-rails on which said table

structure is normally supported and on which said table may be removed, spaced flanged rollers mounted from said supporting structure on which said I-rails are 5 adapted to be rolled transversely of said machine, certain of said rails in extended position forming supports for said table structure when removed from said machine, and other rollers spaced above said first mentioned rollers and cooperating therewith to 10 engage the lower flanges of said I-rails, whereby said rails are supported in unbalanced position.

5. In a paper making machine, a laterally removable table structure, a supporting

structure therefor, track members all mounted on said supporting structure for transverse movement with respect thereto into laterally extended position, all of said track members being normally positioned 20 beneath said table structure during operation of said machine with certain of said track members supporting said table structure, and means for rolling said table structure over the other of said track members 25 when in laterally extended position.

In testimony whereof we have hereunto subscribed our names.

ALONZO ALDRICH.
EARL E. BERRY.
